UNITED STATES PATENT OFFICE.

BARTHOLOMEW T. TREAHY, OF DETROIT, MICHIGAN.

TRANSFORMING AND TRANSPOSING DEVICE FOR AUTOMATIC INSTRUMENTS.

1,018,791.

Specification of Letters Patent.

Patented Feb. 27, 1912.

Application filed January 22, 1910. Serial No. 539,531.

To all whom it may concern:

Be it known that I, BARTHOLOMEW T. TREAHY, a subject of the King of Great Britain, residing at Detroit, in the county of Wayne and State of Michigan, have invented certain new and useful Improvements in Transforming and Transposing Devices for Automatic Instruments, of which the following is a specification.

10 This invention relates to automatic musical instruments, such for example as automatic piano players operated by pneumatic means.

15 An object of the invention is to provide improved means for transposing, that is for varying the key in which the music is played.

Another object of the invention is to provide improved means for adjusting the instrument to accommodate the same to note sheets of different kinds, as for a sixty-five 20 or an eighty-eight note sheet. The invention serves these two functions, that is transposing with respect to key and adjusting with respect to note sheet, in a single mechanism, 25 which may be manipulated to effect either or both of said purposes.

The transposing devices are applicable to an instrument using only one kind of a note sheet; and the adjusting devices are applicable 30 where no transposition is desired.

As illustrated, the tracker is shown provided with two sets of holes, suitable respectively for sixty-five or eighty-eight note sheets, and ducts lead from each set of holes 35 to the transposing and adjusting devices, which devices are located between the tracker board and the primary pneumatics, and include members which can be shifted lengthwise, or across the instrument to 40 transpose, or laterally back and forth to connect or disconnect the respective ducts of the two sets of holes in the tracker.

The devices may be used upon instruments where two different trackers are used or 45 where there are two sets of holes of a different size and spacing in the tracker, and either tracker or set of tracker ducts can be made to register with the passages to the primary pneumatics according to the different kinds of note sheets used.

The invention will be more fully under-

stood from the following description and the accompanying drawings in which—

Figure 1 is a front view of the tracker and spool box. Fig. 2 is a left end view of 55 the same. Fig. 3 is a plan view of the device, removed. Fig. 4 is a section on the line 4—4 of Fig. 3.

Referring specifically to the drawings, 6 indicates the frame of the spool box, 7 the 60 spool therein, 7^a the note sheet roll, and 8 the tracker. This is shown as provided with two sets of holes, 9 and 10, the former being suitable for a sixty-five note sheet and the latter for an eighty-eight note sheet. Obviously 65 this may be varied according to the note sheet used, or substitute trackers may be employed for different note sheets. The ducts 65 lead from the holes 9, and the ducts 88 lead from the holes 10, these ducts being 70 flexible.

Each set of ducts leads to a corresponding set of ports 11 and 12 in a slidable plate or bar 13 which is made in sections, and which as a whole constitute a shiftable plate 75 or valve bar by movement of which the transposition and adjustment are effected. The bar is made in blocks or sections to insure a close fit and provide against objectionable results of possible warping. Each 80 block is connected to a metal bar 14 by means of pins 15 which work through holes in the bar at a nice fit, and spring 16^a, between the bar and blocks, press the latter to close contact with the coöperating bottom plate 16 85 which is provided with openings to operating or action ducts 17 which lead to the primary pneumatics (not shown). The bottom plate 16 constitutes part of a box or casing which is completed by side strips 18. 90

The metal bar 14 is connected at each end to a cross piece 19, the cross pieces being preferably mortised into the bar to insure rigidity, and fastened as by screws 20. The ends of the cross pieces 19 work under retaining guides 21 fastened to the sides 18 of the box, whereby the parts are held in position, permitting, however, movement of the bar 14 and the sectional plate 13 in two directions, that is, both lengthwise and 100 transversely.

The rear ends of the cross pieces 19 are

- articulated to a shifting and turning rod or rock shaft 22 by means of arms 23 projecting from said rod through enlarged holes 24 in the cross pieces 19. Said rod 22 has longitudinal and turning movement in brackets 25 fastened to the box. The rod 22 is turned by means of a lever 26 which is connected by a link 27 to a bent lever 28 which is fulcrumed at 29 on the side 6 of the spool box, 5
- 10 the front end of the bent lever projecting into convenient position for manipulation by the operator.
- The rod 22 is shifted lengthwise by means of a lever 30 fulcrumed at 31 on a suitable 15 bracket at the end of the box, and having a fork at 32 which engages in a groove 33 in the shifting rod. The lever 30 may be operated by any suitable connection to a button 34 at the front of the instrument. Trans- 20 position is effected by shifting the lever 30 and the rod 22, the latter moving lengthwise. Adjustment with respect to note sheet is effected by turning the rod 22 by opera- 25 tion of the lever 26 by the means described.
- 25 In Fig. 2 the device is shown with connection established to the eighty-eight note sheet tracker. By swinging the lever 26 backwardly the rock shaft 22 will, by means of the arms 23 connected to the pieces 24, 30 carry the bar 14 and the blocks 13 rear- 35 wardly to register the passages 11 with the passages 17 leading to the primary pneumatics, thereby establishing communication between the holes 9 for the sixty-five note sheet and the operative mechanism. By 40 shifting the lever 26 forwardly the rod 22 is turned and the communication is established between the ducts 17 and the eighty-eight note sheet holes. For transportation, the 45 lever 30 is shifted, causing lengthwise movement of the rod 22 and consequently of the sectional plate 13, this section being permitted by the flexibility of the tubes 88 and 65. Accordingly the ducts 11 (or 12) are registered with ducts 17 corresponding to 50 the extent of longitudinal movement of the plate 13. In order to permit these actions in a minimum of space the mouths of the ducts 11 and 12 may be enlarged or cupped, 55 as shown at 50, so that the connection may be effected by relatively small movement. The cupping can only be made transversely or to accommodate the adjusting movement. To position the sliding rod 22 as it is shifted 60 one way or the other, it is provided with a series of notches 51, the distance apart of which corresponds with the distance be- 65 tween the ducts 17, and the flat spring 52 will snap into these notches in the different 70 adjustments. The amount of transposition is controlled by the movement of the lever 30, and half a tone up or down will ordinarily be sufficient, although the move-

ment may be increased if desired. Obviously the arrangement and connection of 65 the levers may be varied to operate the parts in a different way, and various other modifications may be made within the scope of the invention. When the blocks 13 are shifted to either position, the unused ducts 70 therein are covered or disconnected from the operative devices of the action.

What I claim as new is:—

1. The combination of a relatively fixed set of action ducts, a relatively fixed tracker 75 having two sets of holes, a set of flexible ducts connected to each set of holes, and a valve attached to said sets of flexible ducts and movable in one direction to register either set of flexible ducts with the action 80 ducts, and movable in another direction to change the registration of the ducts of the selected set of flexible ducts with those of the action set.

2. The combination of a set of action 85 ducts, a plurality of sets of tracker ducts, and a valve with sets of ducts corresponding to the sets of tracker ducts and arranged to register with the action ducts, said valve being movable in one direction to connect the 90 action ducts with a selected set of tracker ducts, and in another direction to vary for transportation the connection between the ducts of the action set and those of the selected set of tracker ducts.

3. The combination of a set of action ducts, a plurality of sets of tracker ducts, and a valve between said sets, comprising a sliding bar with sets of ducts connected respectively to the sets of tracker ducts and 100 arranged to be registered respectively with the action ducts, said bar being slidable in one direction to connect the action ducts with a selected set of tracker ducts, and slidable in another direction to vary for 105 transposition the connection between the action ducts and those of the selected set of tracker ducts.

4. The combination of a plate having 110 therein the terminals of a set of ducts, a tracker, and a valve bar resting against said plate and having therein rows of terminals of a plurality of sets of ducts leading to the tracker, the said bar being movable sidewise on the plate to register the terminals of either of said sets of ducts with the terminals in the plate, and lengthwise to vary for transposition the registration of the terminals of the selected set with the terminals in the plate.

5. The combination of a plate having duct 115 terminals therein, a bar, a series of blocks carried by the bar and having duct terminals therein arranged to register with said terminals, and resting against the plate, 120 springs in compression between the bar and

said blocks, to press the latter against the plate, and means to shift the bar and blocks to vary the registration of the terminals.

6. The combination of a plate having duct terminals therein, a slide valve movable laterally and longitudinally and resting against said plate and having a plurality of rows of duct terminals arranged to be respectively registered with said terminals,

and means to shift the valve, including a longitudinally movable rock shaft connected to the valve.

In testimony whereof, I affix my signature in presence of two witnesses.

BARTHOLOMEW T. TREAHY.
